(57) **CLAIM**

The ornamental design for a string action gauge for stringed instrument, as shown and described.

DESCRIPTION

FIG. 1 is a perspective view a string action gauge for stringed instrument showing our new design;

FIG. 2 is a first side elevation view thereof;

FIG. 3 is a second side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings are for environmental purposes only and form no part of the claimed design.

1 Claim, 4 Drawing Sheets

FIG. 1

FIG. 2

FIG. 3

Diagram of a guitar neck with 6 strings and 12 frets, showing string height measurements in inches. The neck is labeled with fret numbers 6, 7, 8, 9, 10, 11, 12. The strings are labeled 6, 5, 4, 3, 2, 1. A dashed circle is shown on the 12th fret of the 6th string.

InDec	Electric	Acoustic	Bass			
Action	Low E	High E	Low E	High E	Low E	G
Low	.05	.04	.07*	.06*	.075	.065
Low-Med	.06*	.05*	.08	.07	.085*	.075*
Medium	.065	.055	.09	.075	.105	.095
Med-HI	.07	.06	.10	.085	.11	.10
High	.075	.065	.11	.09	.12	.11

* Most Common   * Fingerstyle Most Common

Measure at the 12th Fret. Top of Fret to Bottom of String (Inches)

String Height = Top of the Line Meets Bottom of String
